SAFETY RAZOR AND DETACHABLE SHARPENING DEVICE THEREFOR

Louis V. Aronson, Newark, N. J., assignor to Art Metal Works, Inc., Newark, N. J., a corporation of New Jersey

Application February 11, 1931, Serial No. 515,038

4 Claims. (Cl. 51—241)

This invention relates to an improved detachable sharpening device for a razor, together with an improved construction of the razor whereby the sharpening device may be readily secured in operative position with respect to the blade.

A more specific object of the invention is the provision of a sharpening disk which in conjunction with structural features of the razor will permit of a ready substitution of the sharpening disk for the guard.

Other objects will be apparent from the following description taken in connection with the drawing, in which

Fig. 1 is a central transverse section through the head of the razor;

Fig. 2 is a central longitudinal section through the head of the razor;

Fig. 3 is a top view of the head of the razor showing the position of the sharpening disk by broken lines;

Fig. 4 is a face view of the operating side of the sharpening disk;

Fig. 5 shows the sharpening disk in operative position on the razor; and

Fig. 6 is a diametral section through the sharpening disk.

The razor may include a handle 10 of any suitable attractive design internally threaded at one end to cooperate with a threaded stud 11 on which is secured an inner clamping or razor blade supporting plate 12 which is provided with studs 13 and 14, the enlarged central portions of which pass through apertures or an elongated slot, if desired, in the razor blade 15 and the outer ends of which are provided with heads 16 and 17 to which the outer clamping plate 18 may be secured by bayonet slot connections, as shown. The outer clamping plate 18 is provided with a suitable matted or roughened portion to facilitate moving the clamping plate into and out of position.

Resting against the upper end of the handle 10 and surrounding the stud 11 is a limiting collar 20 which supports the guard supporting member 21 on which are formed the guards 22 and 23 which may be of any suitable construction, and preferably are provided at each end with a raised portion 24 for spacing the razor blade 15 from the guard proper as clearly indicated in Fig. 1.

The sharpening device may comprise a disk 25, the operating side of which may be provided with concentric and tangential grooves defining, in effect, raised portions, as indicated in Fig. 4, and the outer edge of which may be milled so that the disk may be rotated by rolling it on the hand

or any suitable surface. Mounted on the disk 25 is a sleeve 26 provided with a shoulder at each end, one of which normally presses against a shoulder in a recess in the operating face of the disk, and the other of which constitutes an abutment for a spring 27 bearing against the opposite side of the face of the disk.

When it is desired to sharpen one side of the razor blade the handle 10 is detached, after which the spacing collar 20 and guard member 21 may be withdrawn. The sleeve 26 and the disk 25 may then be assembled on the threaded stud 11, after which the handle 10 is threaded on the stud and is turned until the parts assume the positions shown in Fig. 5 in which the spring 27 presses the disk 25 into operative contact with the edges of the razor blade. The disk then is rotated to sharpen the adjacent sides or faces of both edges of the razor blade.

When it is desired to sharpen the other sides or faces of the edges of the razor blade the upper clamping member 18 is removed and the blade is reversed after which the clamping plate is again applied. The parts are then assembled as described.

As shown in Fig. 2 the guard supporting member 21 may be provided with an alining and spacing stud 29 to cooperate with either one of a pair of alining holes 30 and 31 in the inner clamping member 12.

While for the purpose of disclosure it has been deemed sufficient to illustrate but one modification and to describe this with particularity, it is to be understood that the invention may be carried out by other embodiments which may be apparent to those skilled in the art after this invention is understood, and that the terms in the claims are terms of description rather than terms of limitation.

What I claim is:

1. In a construction of the character described, the combination of a handle, a razor blade securing means, a threaded member connecting said securing means and said handle, and a razor blade sharpening means rotatable about said member as an axis and adapted to be secured in freely rotatable position on said member in operative relationship with respect to a razor blade by operating said threaded connection to draw the razor blade securing means toward the handle.

2. In a device of the character described, the combination of a handle internally threaded at one end, a razor blade supporting means, means for securing a razor blade to said supporting

means, a stud carried by said supporting means threaded to cooperate with the interior threads of said handle, a collar surrounding said stud and adapted to be secured in position upon movement 5 of said supporting means toward said handle, a sharpening disk rotatable on said collar, and spring means cooperating with said collar and said sharpening disk for pressing said disk against a razor blade carried by said supporting 10 means.

3. In combination with a razor including a razor blade supporting plate having an attaching stud, a handle for connection to said stud, and means for supporting a blade on top of said 15 supporting plate; of a sharpening disk mounted to rotate on said stud as an axis and held in freely rotatable position on said stud in func-

tioning relationship to the edges of a blade supported on said plate, by means of said handle.

4. In combination with a razor including a 5 razor blade supporting means comprising an inner flat plate of less width than the razor blade and an outer arcuate clamping or top plate of less width than the razor blade but of greater width than the inner plate for flexing said blade to present the edges of the blade below the plane of the inner surface of said inner plate, a handle, and a stud for securing the handle to the inner plate; of a sharpening disk rotatably mounted on said stud adapted to bear against both the edges of said razor blade and to be held in functioning position by said handle. 10 15

LOUIS V. ARONSON.
